(57) **CLAIM**

The ornamental design for a table, as shown and described.

DESCRIPTION

FIG. 1 is a perspective view of a first embodiment of a table showing my new design;

FIG. 2 is a front elevational view, the rear and sides being a mirror image thereof;

FIG. 3 is a 45° elevational view (90° rotation elevations being mirror images thereof);

FIG. 4 is a top plan view;

FIG. 5 is a bottom plan view;

FIG. 6 is a perspective view of a second embodiment of a table showing my new design;

FIG. 7 is a front elevational view, the rear being a mirror image thereof;

FIG. 8 is a right side elevational view, the left side being a mirror image thereof;

FIG. 9 is a top plan view; and,

FIG. 10 is a bottom plan view.
